(57) **CLAIM**

The ornamental design for lighting, as shown and described.

DESCRIPTION

FIG. 1 is a perspective view of a first embodiment of the design of the present disclosure;

FIG. 2 is a bottom view of the embodiment depicted in FIG. 1;

FIG. 3 is a top view of the embodiment depicted in FIG. 1; FIG. 4 is a left side view of the embodiment depicted in FIG. 1, the right side view being identical to the left side view; and, FIG. 5 is a front view of the embodiment depicted in FIG. 1, the rear view being identical to the front view.

Those portions of the present invention which are presented in phantom illustrate the environment of the design only and form no part of the claimed design. Moreover, the shading presented in the accompanying drawings is provided merely to highlight the contour of the invention and is not intended to be illustrative of texture or gloss.
